UNITED STATES PATENT OFFICE.

ALICE M. BURR, OF BARDAINE, WEST VIRGINIA.

WASHBOARD.

Application filed September 17, 1923. Serial No. 668,160.

To all whom it may concern:

Be it known that I, ALICE M. BURR, citizen of the United States, residing at Bardane, in the county of Jefferson and State 5 of West Virginia, have invented certain new and useful Improvements in Washboards, of which the following is a specification.

This invention relates to wash boards 10 and it has for its object to provide a simple and efficient wash board with a metal rub surface which shall be very durable, while at the same time providing for quicker and easier washing of the goods.

15 The primary object of the invention is to provide a wash board which embraces the desired qualities of simplicity, durability and efficiency in operation.

A further object of the invention is to 20 provide a wash board having a metal rub surface which is pervious and possesses every quality for the thorough washing or rubbing of goods, the board further embodying a place of rest for the soap when the latter 25 is not in use, so formed as to insure draining of the water from the soap during that time.

Other objects will appear as the nature 30 of the invention is better understood and the same consists in the novel form, combination and arrangement of parts hereinafter more fully described, shown in the accompanying drawing and claimed.

In the drawing, wherein like reference 35 characters indicate corresponding parts in the two views:

Figure 1 is a front elevational view of a washboard constructed in accordance with the present invention, and

40 Figure 2 is a fragmentary enlarged transverse sectional view thereof.

Referring more in detail to the drawing, the washboard consists of a frame constructed in any preferred or well known manner, and consisting of opposite side bars 45 5 preferably having inner side grooves as at 6, and connected rigidly by means of upper and lower transverse or cross bars 7 and 8 respectively, said bars 7 and 8 being also preferably provided with central longitudinal grooves upon their inner sides.

The rub surface consists of a woven wire fabric in which the series of longitudinal warp wires 10 are woven or interlaced about the series of transverse weft wires 55 10, said weft wires being also interlaced reversely about the longitudinal warp wires

10, so as to have an angular projection at each side of the warp wires, as shown at 11, in Figure 2. The warp and weft wires are uniformly spaced apart so that the fabric 60 employed is of a rectangular mesh with the wires closely related to such an extent as to not leave too large spaces between the wire.

The warp and weft wires at the edges 65 of the wire fabric are bent around a heavy wire rectangular frame, as indicated at 12 in Figure 2, so that a substantially rigid construction is had for preventing the warp and weft wires loosening and unravelling at 70 the edges, the frame 12 being seated within the grooves 6 of the various frame bars 5, 7 and 8.

Disposed against opposite sides of the rub 75 surface or wire fabric and rigidly connecting the side frame bars 5 adjacent to but spaced from the frame bar 7 are further transverse bars, one of which is shown at 13 in Figure 1. The bars 7 and 13 and the wire fabric therebetween, together with the 80 adjacent portions of the side frame bars 5 provide a soap box at both sides of the board, the bottom of which is pervious for permitting ready draining of the water from the soap.

In case a single surface board is desired, with a cross bar 13 only employed at one side of the board, the other side of the rub surface may be provided with longitudinal reinforcing wires 14 consisting of heavy twisted 90 wire members of comparatively rigid form which are spaced substantially equal distances from each other and from the side bars 5 and which have their ends rigidly connected in any desired or preferred manner 95 to the top and bottom frame bars 7 and 8. Reinforcing bars or heavy wires 14 are positioned so as to contact the rear surface of the rub surface and by reason of the position of the same, said rub surface is effectively braced and supported against strains imposed thereon during the washing operation, thus insuring a longer life of the board.

The wires comprising the woven wire fabric rub surface and the frame 12 as well 100 as the reinforcing bars 14 may be made of zinc, aluminum, or any other suitable metal that will not readily rust.

It will, of course, be understood that the frame of the wash board will be constructed 110 in any suitable manner other than that described and may be made of wood or metal

and it will be understood that changes in the form, proportion and the minor details of construction may be resorted to without departing from the spirit and scope of the 5 invention as claimed.

What I claim as new is:

1. In a wash board, the combination with opposed side frame bars rigidly connected by upper and lower transverse frame bars, 10 a woven wire fabric rub surface supported between the upper, lower and side frame bars, a transverse bar connecting the side frame bars adjacent the upper frame bar and spaced from the latter as well as disposed upon one surface of said wire fabric to provide a soap box at the upper end of the board having a pervious bottom formed by a portion of said fabric, and relatively 15 rigid longitudinal reinforcing wires disposed against the other surface of the wire fabric and connecting the top and bottom frame bars.
2. In a wash board, the combination with opposed side frame bars rigidly connected by upper and lower transverse frame bars, 25 a woven wire fabric rub surface supported between the upper, lower and side frame bars, a transverse bar connecting the side frame bars adjacent the upper frame bar and spaced from the latter as well as disposed upon one surface of said wire fabric to provide a soap box at the upper end of the board having a pervious bottom formed by a portion of said fabric, and relatively 30 rigid longitudinal reinforcing wires disposed against the other surface of the wire fabric and connecting the top and bottom frame bars, said reinforcing wires consisting of twisted wires and being substantially 35 uniform and spaced apart from each other and from the side frame bars.

In testimony whereof I affix my signature.

ALICE M. BURR.
